FOUNTAIN APPLICATOR

Albert E. Neely, Chicago, Ill., assignor to Dupli-Color Products Company, Inc., Chicago, Ill., a corporation of Illinois

Application July 18, 1955, Serial No. 522,464

9 Claims. (Cl. 15—139)

This invention relates to a fountain applicator or fountain brush, and has particular reference to means providing air-tightness during periods of non-use of such a device.

A common function of valved fountain brushes of a type of which the present invention is concerned, is the storing and the brush-dispensing of such materials as quick-drying paints, lacquers, enamels and stains, or like fluids having highly volatile solvents. Such materials quickly become almost useless for brush-dispensing when exposed to air for any extended duration of time; for when so exposed, if they do not dry out altogether, they form crusts or the like which render them unsuitable for dispensing through a valved orifice and spreading by a brush.

To aggravate the problem, such materials are often of a type which may likely not be used except after prolonged periods of non-use. For example, the material may be the so-called "touch-up" paint for occasional use by a motorist to cover scratches or the like in the painted surface of his automobile. In a fountain applicator or fountain brush for such a use, it is particularly desirable that highly effective sealing means be provided to prevent the material from drying out.

It is thus an object of the present invention to provide new and improved sealing means for a fountain applicator or fountain brush.

Another object is to adapt a standard bottle having a screw thread neck for use as the reservoir and nozzle carrier of a fountain brush.

It is another object of my invention to provide a multiple-type sealing means for such a device of the type having a screw-attachable cap, which will provide positive and highly effective means for sealing a plurality of mating surfaces in response to the single action of screwing in a normal manner the cap onto the body of the device.

A further object of my invention is the provision of nozzle sealing means in an economical manner.

Other objects, features, and advantages of the present invention, with relation to a general and specific improvement of fountain applicators and brushes, will be readily apparent from the following description of certain preferred embodiments thereof, taken in conjunction with the accompanying drawing, in which:

Figure 1 is a side elevational view of the applicator and closure cap assembly of this invention, and shown in closed position;

Figure 2 is an end view of the cap shown in Fig. 1;

Figure 3 is a vertical cross-section of the applicator without the cap, taken along the line III—III of Fig. 1;

Figure 4 is a view similar to Fig. 3, showing the cap being applied to the nozzle of the applicator;

Figure 5 is a view similar to Fig. 3, showing the cap in place as screw-threaded onto the applicator body;

Figure 6 is a horizontal section taken on the line VI—VI of Fig. 5; and

2

Figure 7 is a view similar to Fig. 5, but showing an alternative construction.

As shown on the drawings:

The applicator or fountain brush 10 includes a body 12, preferably in the form of a glass, plastic or metal bottle and forming a fluid reservoir chamber or barrel which is adapted to be closed by a closure cap 13. As shown, the body 12 has a neck 14 of cylindrical configuration terminating at a neck mouth 16, and that neck 14 is provided on its exterior with screw threads 18 which mate with corresponding screw threads 19 carried by the cap of the device to permit the user to bring the cap 13 and body 12 into assembled relationship.

The present invention principally concerns the means provided for effecting an efficient sealing of the liquid carried by the body 12 of such a device, with the sealing means being effected upon tight assembly of the cap 13 onto the body 12.

A stopper or plug 20 is fitted into the neck 14 of the body 12. The plug 20 desirably is formed of a resilient plastic material, such as nylon or polyethylene. A preferred embodiment of the plug 20, clearly shown in section in each of Figs. 3, 4, 5 and 7, comprises an integrally-molded member having a central bore and generally cylindrical side wall or cylindrical type sleeve 24 adapted to snugly be received in the neck 14 of the body 12, and a transversely extending annular flange 28 adapted to lie over the circular mouth 16 of the body neck 14. An annular spacing web 30 extends inwardly from the sleeve 24, and carries at its inner periphery a cylindrical type sleeve 32 which is adapted to snugly receive a cylindrical stem 34 of an associated nozzle 35 yet to be described. The base of the nozzle 35 is seated on an annular abutment such as the shoulder or flange 38 which extends inwardly from the sleeve 32, said flange 38 provided with a central opening 49, otherwise not imperforated.

The nozzle 35 is provided at its free end 39, that is the end opposite stem 34, with an orifice 44 for the dispensing of fluid by means of an associated applicator or brush assembly 45, comprising in the exemplary form shown elements 46—48. A valve plug 46, which carries the bristles 47 of the applicator brush, is carried at the end of a plunger stem 48, and the plunger 48 is adapted to bias plug 46 toward orifice-closing position by a coil spring 50 one end of which bears against the plug 46 and the other end of which is bottomed against flange 38 of the body-plug 20. The stem of plunger 48 is slidably received in an opening 49 provided in plug-flange 38, and that opening also permits the liquid to flow from the body 12 into the nozzle 35.

The plunger is guided within nozzle 35 by means of lugs 54 radially extending from the plug 46 for guided sliding relationship along the interior bore of the nozzle 35.

With a dispensing nozzle as shown, the liquid to be dispensed flows from the interior of the body 12 through plug opening 49 and into the hollow interior of the nozzle 35. The orifice 44 at the free end of the nozzle is normally closed by the plug 46, blocking passage of the material through that orifice 44 to the bristles 47. The arrangement is such that when the material on the bristles 47 becomes exhausted, the user pushes down on the applicator body 12, forcing the bristles 47 and the plunger 48 upwardly relative to the nozzle 35, against the bias of spring 50, thereby retracting the valve plug 46 and permitting a further charge of material to flow through the orifice 44 and onto the bristles 47.

The closure cap generally referred to above by reference numeral 13 conveniently comprises a rigid outer shell 60, which may be conveniently molded from a plastic

material such as Bakelite, having a closed hollow interior into which is fitted a sealing cup sleeve or liner 62. The cup sleeve 62 is formed of a resilient material such as plastic of the type of nylon or polyethylene, and the sleeve is desirably held in place in the shell 60 by the frictional grip between the juxtaposed surfaces of the two parts. In the embodiment shown in Figs. 4, 5 and 6, the end or closed bottom 63 of the cup sleeve 62 carries an upstanding pin-like projection 64 adapted to penetrate the brush bristles and engage the nozzle plug 46 during assembly of the closure cap 13 onto the body 12 to force a withdrawal of the brush bristles 47 into a protected position within the nozzle 35, as shown in Fig. 5. It should be noted that the stem of the pin 64 is tightly engaged by the end of the cup sleeve 62 while the head 65 of the pin is clamped between the closed end of the shell 60 and the closed end 63 of the cup sleeve. If desired, the head 65 can be seated in a recess 68 formed in the shell.

As shown in Fig. 4, the cap is in a position of initial address onto the body 12. As there shown, it is in a cocked or off-center relation with the body. However, the elongation of the cap past the end of pin 64 cooperates with the nozzle 35 to effect a self-alignment which positions pin 64 centrally of the nozzle.

Below the threads 19 on the mouth of the cap 13, the cap shell 60 extends inwardly to provide a radial annular shoulder 74 adapted to engage the flange 28 of the body plug 20. As the cap is drawn toward the applicator body 12 by the interengaging threads 18-19, the shoulder 74 is bottomed against the plug flange 28 to a clamp the flange between the shoulder and the mouth 16 of the bottle neck. This provides part of the sealing feature of the present invention.

A second seal is created between the orifice end of the nozzle and the closed end of the cup liner 62 as shown in Fig. 5 when the cap is threaded on the bottle neck. As therein shown the end wall 63 of the liner is forced against the nozzle end 39 to seal the orifice 44.

A third seal is created between the stem portion 34 of the nozzle and the plug 20 when the end of the stem is forced against the plug flange 38 by the end thrust exerted from the cap liner being bottomed on the nozzle end 39. The forcing of the stem end against the plug flange 38 tends to stretch the plug sleeve thereby reducing its diameter and causing the sleeve to more tightly embrace the stem.

The multiple seal thus includes a clamped plug flange between the cap shoulder and bottle mouth thereby providing a gasket seal; a resilient liner wall pressed over the orificed end of the nozzle thereby providing a sealing cap for the orifice; and a stressed plug sleeve and flange embracing the stem portion of the nozzle thereby providing a nozzle seating seal. All of these seals are automatically obtained when the cap 13 is threaded home on the bottle neck 14.

In the modification illustrated in Fig. 7 parts substantially identical with parts shown in Figs. 1 to 6 have been marked with the same reference numerals. As shown in Fig. 7, the modified applicator 10a includes the bottle 12, the plug 20, and the nozzle 35 of the device 10. However, the guide lugs 54 on the brush assembly 45 are eliminated. Also eliminated is the brush retracting pin 64, for in the embodiment illustrated in Fig. 7, closure of the cap does not effect a retraction of the brush assembly, but rather, provides means for receiving the bristles 47 in an extended position. To this end, a different cap 13a is provided, in which the cap shell 60a is formed to provide a well or pocket 61a at its closed end. A resilient liner means such as the cup-like sleeve 62a having tapered side-walls 62b and a bristle-receiving well such as the pocket 62c covers that closed end of the cap 60a and pocket 61a. The liner is formed of a shape which presents its side-wall portion 62b smoothly tapering to merging with its well or pocket 62c,

providing a generally smooth wall for guiding the bristles 47 into the pocket 62c upon assembly of cap 13a with the body 12.

It should be noted that clearance 80 is provided between the end wall of said liner-pocket 62c and the bristles 47 in extended position, thereby assuring against cramping of those bristles when the cap 13a is assembled onto the body.

In this Fig. 7 embodiment, threading cap 13a onto the body 12 causes sleeve side-wall 62b to engage nozzle end-portion 39. This effects a sealing relationship effectively sealing the nozzle orifice 44. A second seal is effected by the thrust sustained by the nozzle, for that thrust forces nozzle 35 into sealing relationship with the abutment flange 38. The thrust on the abutment flange 38 tends to stretch plug sleeve 32 which carries that flange 38, thereby causing the sleeve 32 to more firmly embrace the nozzle end-portion 34 and effectuate an additional seal. Further sealing is obtained as the flange 38 and sleeve 32 are urged into the bottle 12, for they pull on the plug flange 28 to cause it to sealingly engage the bottle mouth 16 on which it is seated.

Thus, a device according to either embodiment of my invention is provided with a multiplicity of seals to give positive and effective sealing of the applicator contents from the outside atmosphere, and those seals are obtained in response to a single action of screwing cap 14 to the body 12 in a normal manner.

It will thus be seen that the present invention provides a new and improved fountain applicator having the desired advantages and characteristics, and accomplishing its intended objects, including those hereinbefore pointed out and others which are inherent in the invention as described.

It will be understood that modifications and variations may be effected without departing from the scope of the novel concepts of the present invention.

I claim as my invention:

1. A device of the type described, comprising a hollow body adapted to contain liquid therein, said body including a mouth, a nozzle projecting outwardly from the mouth of said body, a plug member formed of resilient material providing a radially outwardly extending flange, a first annular sleeve, a second annular sleeve and a radially inwardly extending flange, said radially outwardly extending flange being seated on said mouth, said first annular sleeve being snugly received in said mouth, said second annular sleeve snugly receiving the base end portion of said nozzle, said radially inwardly extending flange presenting an end abutment in said second annular sleeve, the base end portion of said nozzle being seated on said abutment, a removable closure cap embracing said nozzle, said cap having an end seal overlying the nozzle end to seal the nozzle, thread means interconnecting said cap and said body, said cap having an internal shoulder seating on said radially outwardly extending flange and bearing thereon in response to tightening of said cap onto said body to effect a sealing engagement of said cap onto said flange and said flange onto the mouth of the body, said overlying end seal of said cap forcing the base end of said nozzle into sealing engagement with said end abutment while the shoulder is bottomed on the radially outwardly extending flange in response to tightening of said cap onto said body.
2. A device of the type described, comprising a hollow body adapted to contain liquid therein, said body including a mouth, a nozzle projecting outwardly from the mouth of said body, a plug member formed of resilient material and providing a radially outwardly extending flange seated on said mouth, said plug member embodying a first annular sleeve means snugly received in said mouth, said plug member embodying a second annular sleeve means snugly receiving the base end portion of said nozzle, said plug member embodying a radially in-

wardly extending flange presenting an end abutment in said second sleeve means, said abutment having a central opening, but otherwise imperforated, the end portion of said nozzle being seated on said abutment, a removable closure cap; thread means interconnecting said cap and said body, said cap having an annular shoulder seating on said radially outwardly extending flange and bearing thereon in response to tightening of said cap onto said body to effect a sealing engagement of said cap onto said flange and said flange onto the mouth of the body, said cap having means engaging said nozzle to force the base end of said nozzle into sealing engagement with said radially inwardly extending flange in response to tightening of said cap onto said body.

3. A device of the type described, comprising a hollow body adapted to contain a supply of liquid therein, said body including a neck portion with a mouth, a nozzle projecting outwardly from the mouth of said body, a plug member formed of resilient material and providing a radially inwardly extending flange, a first cylindrical sleeve means, a second cylindrical sleeve means and a radially inwardly extending flange, said radially outwardly extending flange being seated on said mouth, said first sleeve means being snugly received in said mouth, said second sleeve means snugly receiving the base end portion of said nozzle, said radially inwardly extending flange presenting a surface having seated thereon the stem of said nozzle, a removable closure cap, means for drawing said cap and said body into assembled relationship, said cap having flange means seating on said radially outwardly extending flange and bearing thereon to effect a sealing engagement of said cap onto said flange and said flange onto the mouth of the body, the inner surfaces of said cap bearing against one end of said nozzle to force the opposite end into sealing engagement with said radially inwardly extending flange in response to tightening of said cap onto said body.

4. A device of the type described, comprising a hollow body adapted to contain liquid therein, said body including a mouth, a substantially cylindrical type nozzle projecting outwardly from the mouth of said body, a plug member formed of resilient material and providing a radially outwardly extending flange, a first cylindrical sleeve member, a second cylindrical sleeve member, and an annular abutment means extending inwardly of said second sleeve member, said radially outwardly extending flange seating on said mouth, said first sleeve member being snugly received in said mouth, said second sleeve member interiorly snugly receiving the base portion of said cylindrical nozzle, and said annular abutment means extending inwardly of said second cylindrical sleeve member having a cylindrical opening, but otherwise imperforated, and having seated thereon the stem of said nozzle, a removable closure cap, means for drawing said cap and said body into assembled relationship, said cap having flange means seating on said radially outwardly extending flange and bearing thereon to effect a sealing engagement of said cap onto said flange and said flange onto the mouth of the body, said cap including a resilient liner means bearing against the outlet end of said nozzle in sealing relationship therewith in response to drawing of said cap into assembled relationship with said body to force the base end of said nozzle into sealing engagement with said annular abutment means.

5. A device of the type described, comprising a hollow body adapted to contain a supply of liquid therein, said body having a cylindrical neck including a mouth, a plug member having a central opening, but otherwise imperforated, assembled within said neck and in sealing contact with said mouth, said plug member formed of resilient material to integrally provide a radially outwardly extending sealing flange means, a cylindrical sleeve means and a seat means, said radially outwardly extending

flange means being seated on said mouth, a nozzle projecting outwardly from the mouth of said plug member, said sleeve means carrying said nozzle, said seat means seating said nozzle, a removable closure cap, said cap having means engageable with a portion of said nozzle adjacent the outlet end thereof when said cap is assembled onto said body to urge the base of said nozzle against said seat means in a sealing relationship therewith and to stress said cylindrical sleeve means to thereby urge said radially outwardly extending sealing flange means against said body mouth in a sealing relationship therewith.

6. A fountain applicator which comprises a bottle having an exteriorly threaded neck, an orificed nozzle projecting from said neck, an applicator assembly carried by said nozzle, an adapter plug arranged between said nozzle and said neck, and a closure cap for the bottle, said plug having a radially outwardly extending flange, a first cylindrical sleeve member, a second cylindrical sleeve member and a radially inwardly extending flange, said first cylindrical sleeve member snugly fitting in said neck, said second cylindrical sleeve member snugly receiving the base end portion of said nozzle therein, said cap being provided with an internal shoulder and having internal screw threads at the open end thereof engaging the threads on said neck, a resilient insert arranged upon the inner walls of said cap for engaging the nozzle adjacent the discharge end thereof to seal the orifice thereof and said cap when threaded onto the bottle neck causing said insert to sealingly engage the free end portion of said nozzle, the base end of the nozzle to sealingly engage the radially inwardly extending flange of said plug, and said cap shoulder to sealingly engage the radially outwardly extending flange.

7. A fountain applicator which comprises a bottle having an exteriorly threaded neck, an orificed nozzle projecting from said neck, an applicator assembly carried by said nozzle, an adapter plug between the nozzle and bottle neck, and a closure cap for the bottle, said plug having a radially outwardly extending flange, a first cylindrical sleeve member, a second cylindrical sleeve member and a seat means, said first sleeve member fitting in said neck, said second sleeve member snugly receiving an end portion of said nozzle therein, said seat means seating said nozzle, said cap having internal screw threads adjacent the open end thereof for engaging the threads on said neck, and means carried by the interior wall of said cap engaging the nozzle adjacent the outlet end thereof and the radially extending plug flange to urge the base end of the nozzle into sealing relationship with said seat means of the plug, and the radially outwardly extending flange of said plug to sealingly engage the neck of said bottle.

8. A fountain applicator which comprises a bottle having an exteriorly threaded neck, an orificed nozzle projecting from said neck, an applicator assembly carried by said nozzle and including a dispensing brush means extending therefrom through the orifice thereof, an adapter plug between the nozzle and the bottle neck, and a closure cap for the bottle, said plug having a radially outwardly extending flange, a first sleeve member, a second sleeve member, and a radially inwardly extending flange, said first sleeve member snugly fitting in said neck, said second sleeve member snugly receiving the base end portion of the nozzle therein, said radially inwardly extending flange having an aperture therein, but otherwise imperforated, said cap having internal screw threads engaging the threads on said neck when threaded thereon, a resilient insert carried upon the inner walls of said cap engaging the exterior of said nozzle about the orifice outlet and operative to seal the orifice thereof when the cap is threaded on the bottle neck, and said cap when threaded onto the bottle neck causing said insert to move axially to sealingly engage the nozzle adjacent the outlet end thereof, the base end of the nozzle to move axially and seal-

ingly engage said radially inwardly extending flange of said plug, and the radially outwardly extending flange of said plug to move axially and sealingly engage the neck of said bottle, said resilient insert being formed to provide a well for receiving the dispensing brush when said cap is closed onto said body.

9. A fountain applicator which comprises a bottle having a cylindrical exteriorly threaded neck including a mouth portion, an orifice nozzle projecting from said neck, an applicator assembly carried by said nozzle and including a dispensing brush means extending therefrom through the orifice thereof, an adapter plug between the nozzle and bottle neck, and a closure cap for the bottle, said plug having a radially outwardly extending flange, a first sleeve member, a second sleeve member and a radially inwardly extending flange, said first sleeve member snugly fitting into said neck, said second sleeve member snugly receiving the base end portion of the nozzle therein, said radially inwardly extending flange having an aperture therein, but otherwise imperforated, said cap having 15 internal screw threads adjacent its open end for engaging the threads on the neck, a resilient insert in said cap for engaging the nozzle about said orifice and operative to seal the orifice thereof when the cap is threaded on the

5

10

20

neck, and said cap when threaded onto the bottle neck moving the insert axially to sealingly engage the free end of the nozzle, the base end of the nozzle to sealingly engage the radially inwardly extending flange of said plug, and the radially outwardly extending flange of said plug to sealingly engage the bottle neck and mouth portion, said resilient insert being formed to provide a well for receiving the dispensing brush means when said cap is closed onto said body, said insert diverging from said well to provide a guide surface smoothly tapering to and merging with said well to smoothly guide said dispensing brush means into said well during assembly of said cap onto said body.
